UNITED STATES PATENT OFFICE.

JULIUS JOE SCHUERMANN, OF CLINTON, IOWA.

PHOTOGRAPHER'S HEAD-SCREEN.

1,378,904.

Specification of Letters Patent. Patented May 24, 1921.

Application filed September 2, 1920. Serial No. 407,666.

To all whom it may concern:

Be it known that I, JULIUS J. SCHUERMANN, a citizen of the United States, residing in Clinton, county of Clinton, and State of Iowa, have invented certain new and useful Improvements in Photographers' Head-Screens, of which the following is a specification.

This invention relates to screens used by 10 photographers for obstructing or reflecting light or correcting or modifying the illumination of subjects or objects being photographed, such as the head of a person.

The screen ordinarily used for the purposes above mentioned, comprises an annular frame supporting a fabric and attached to an adjustable rod carried by a vertically adjustable standard.

The principal object of my invention is 20 to provide an improved way of attaching the fabric or cover to the annular frame and to make the annular frame collapsible, *i. e.*, in sections which can be readily removable and taken apart so as to occupy a small 25 space. A further object of the invention is to provide means whereby the entire device may be collapsed and made to occupy a small space, rendering it readily portable.

In carrying out my invention I provide an 30 annular frame made in sections, provided with locking devices or catches, whereby they may be quickly connected and as readily separated. The frame is provided with a threaded boss to receive one end of a supporting rod and the fabric is preferably formed with a hem within which is inclosed an elastic band which enables the fabric to be stretched at its periphery while being applied to the frame and to be then automatically tightened when properly applied. 35 The hemmed portion is turned over toward the middle of the cover, providing an annular space to receive the annular frame and the edge portion of the cover is formed with a hole to receive a boss carried by one of the annular frame sections, the arrangement being such that in applying the cover to the annular frame the boss is passed through the hole and then the cover is applied to the annular frame by having its 45 peripheral portion opened up and then released progressively around the entire frame. In this way the cover may be separately formed and provided with means 50 for attaching it to the frame and after the

cover is applied to the frame no other fastening devices or stitching is required.

In the accompanying drawings—

Figure 1 is a perspective view of a head screen complete embodying my improvements; 60

Fig. 2 is a detail view in vertical section of the post or standard of the stand to which the head screen is applied;

Fig. 3 is a detail view in section showing 65 how the inclined supporting rod of the screen is connected with the annular frame and it also shows one of the catches or locking devices for connecting the sections of the annular frame; 70

Fig. 4 is a detail view in perspective, further illustrating such locking devices;

Fig. 5 is a perspective view showing how 75 the annular frame sections, the inclined supporting rod and the fabric covering may be taken apart and assembled to occupy a small space;

Fig. 6 indicates the best method of applying the cover to the annular frame;

Fig. 7 shows the annular frame completely covered by the fabric; 80

Fig. 8 is a perspective view indicating 85 how the entire device, including the stand, the annular frame, the inclined supporting rod and the cover, may be folded, collapsed and brought together to occupy a small space, which makes it readily portable.

Fig. 9 is a detail view of the devices for joining the screen-supporting rod to the stand. 90

The head screen is supported on a stand A, comprising a post or standard having a tubular section a , carrying a frame a^2 , to which are hinged supporting legs b , connected by links b' , to another frame b^3 , carried by a tubular telescoping section a' , the arrangement being such that the legs may be swung inward toward the post to occupy a substantially parallel relation therewith. The section a carries a spring catch C, having a lug c , operating through a hole in the section a and adapted to engage a hole c' in the section a' . When the catch engages the two holes c', c^3 , the post sections a and a' are locked, but by pressing on the lug c 100 the locking devices may be released and the post sections made to move longitudinally, the one over the other.

The section a has a telescopic connection with the section a^4 and carries a catch C' 110.

adapted to engage the hole c^2 in the section a^4 . The catch C' operates in a similar manner to the catch C . By these devices the length of the post may be varied and the screen may be held at any desired elevation. The stand as a whole may be collapsed and made to occupy a small space. Two of the legs 1^b and 2^b are longer than the others and extend under the screen. In this way the 10 overturning of the stand by the weight of the screen is prevented. The links b' which connect the legs 1^b and 2^b to the frame b^3 are slotted as indicated at s and these slots receive pins s' carried by the legs. In 15 this way all four legs may be readily collapsed and made to lie straight and parallel with the stand.

A clamping device D is applied to the top of the section a^4 . It may be made detachable therefrom. It comprises clamping disks d and a screw d' . The clamp carries a rod G , which supports the screen proper. This rod may be adjusted lengthwise in the clamp and the clamp may be 20 turned so as to hold the rod at any desired inclination.

By reference to Fig. 9, it will be observed that the disks d are supported on a bracket M which extends upwardly from a plug m which fits into a round hole in a block m^2 secured as indicated at m' to the upper section a^4 of the stand. The plug is free to turn to a limited extent about a vertical axis, its movement being limited by a lug m^3 which it carries and which moves in a recess n formed in the upper end of the block m^2 . N indicates a set screw, passing through the section a^4 and the block m^2 and adapted to bear against the plug m . By 30 this construction the plug, and the devices which it carries, may be lifted from the stand and it may be readily applied to the stand, the downward movement of the plug m being limited by the lug m^3 which enters the recess n . The plug m may turn about a vertical axis and may be held, when once adjusted, by the set screw N . In this 40 way the position of the screen may be changed without altering the position of the stand.

The outer end of the rod G is threaded and engages a boss g on one of the frame sections of the screen. When it is desired to make the screen as a whole portable, the rod G may be readily detached from the boss of the screen and it may be detached from the clamp D , or the clamp D with the rod may be detached from the post of the stand.

The screen proper comprises an annular frame H and a cover F . The fabric cover is substantially circular in form and it is provided on its periphery with an edge portion f which is turned over toward the middle of the cover but this edge portion is not 50 secured to the cover so that it may be turned

back when desired. The edge portion of the cover is formed with a hole f' through which the boss g on the frame ring may be passed. Preferably the edge of the screen is provided with a hem f^3 within which is arranged an elastic band f^2 , the ends of which are shown in Figs. 1 and 7. While it is not essential that an elastic band be used, I prefer to employ it as it facilitates in the adjustment of the cover on the frame. 75

In applying the cover to the frame ring the boss g is first passed through the hole f' , (Fig. 6) and the edge portion of the cover is progressively folded over the ring in the manner shown in Fig. 6. When the 80 cover is completely applied, as shown in Fig. 7, the screen is ready to be secured to the outer end of the inclined rod G .

It will be observed that the cover may be made complete of any suitable fabric and 85 without change in construction it may be quickly applied to the frame ring. No stitching is required or additional fastenings for securing the cover to the frame ring when they are associated in the manner 90 above described. The cover may be readily detached from the frame ring by disconnecting the boss g from the rod G and then turning the edge portion of the cover back over the frame. 95

The frame ring, it will be observed, is made in separable sections in order that it may be reduced in size to occupy a small space for storage or transport, and it may be associated with the stand sections, supporting rod and cover in the manner indicated in Fig. 8. Any desired number of ring sections may be used and any suitable locking or fastening devices for connecting the frame sections may be employed. One 100 of the frame sections is equipped with the boss g above referred to, which may be applied to a frame section in the manner indicated in Fig. 3, the boss g being formed on a sleeve g' , fitting a frame section. The 105 locking devices may be of any suitable kind, preferably of the kind illustrated. The frame sections are preferably all tubular. One frame section contains a block h , formed with a slot h^2 , and this section is 110 formed with a hole h' to receive the catch. The adjacent end of another ring section is provided with a plug i , having a tongue i' adapted to enter the slot or recess h^2 in the plug h . The section which carries the plug i also carries a spring catch K , the spring 115 of which is attached at h' to the section and carries a lug h adapted to pass into the hole h' of the adjacent frame section. When the two adjacent ends of the frame 120 sections are brought together the spring catch engages the hole h' and the tongue i' enters the recess h^2 . In this way a very firm joint is made but this joint may be broken and the sections separated by merely 125

130

pressing on the catch. The several sections may be connected in a similar way and other devices may be employed for locking the sections and for detaching them, my invention 5 principally relating to means broadly considered for making the annular frame in detachable sections so that the screen as a whole may be collapsed and in providing an improved way for applying the fabric or 10 cover to the frame.

I claim as my invention:—

1. A photographer's head screen comprising an annular frame and a fabric cover having an edge portion turned over toward the 15 middle of the screen and inclosing the annular frame.

2. A photographer's head screen comprising an annular frame, a fabric cover having an elastic band at its periphery and having 20 an edge portion turned over toward the middle of the screen and inclosing the annular frame.

3. A photographer's head screen comprising a sectional, annular frame provided with 25 a boss and a fabric cover therefor having an edge portion turned over toward the middle of the screen which is formed with a hole to receive the boss carried by the frame and which is adapted to receive a supporting rod.

30 4. A photographer's head screen comprising a sectional, annular frame provided with a boss, a fabric cover therefor having an elastic band at its periphery and an edge portion turned over toward the middle of 35 the screen which is formed with a hole to receive the boss carried by the frame and which is adapted to receive a supporting rod.

5. A photographer's head screen comprising 40 an annular frame made in sections having locking devices at their ends and one of which is provided with a boss adapted to connect with a supporting rod, and a fabric cover for the annular frame having a hole to receive the boss and having also a peripheral portion of the fabric turned over on the frame toward the middle of the screen.

6. A photographer's head screen comprising 45 an annular frame made in sections having locking devices at their ends and one of which is provided with a boss adapted to connect with a supporting rod, and a fabric cover for the annular frame having an elastic band in its periphery and a hole to receive the boss and having also a peripheral portion of the fabric turned over on the frame toward the middle of the screen.

7. A photographer's head screen comprising

ing a stand composed of collapsible legs and a collapsible post, a clamp carried by the 60 post, an inclined supporting rod detachably connected with the clamp, a screen proper detachably connected with the inclined connecting rod and comprising detachable ring sections connected by locking devices, and a 65 fabric cover removably connected with the frame ring.

8. A photographer's head screen comprising a stand composed of collapsible legs some of which are longer than the others and a 70 collapsible post, a clamp carried by the post, an inclined supporting rod detachably connected with the clamp, a screen proper detachably connected with the inclined supporting rod, and comprising detachable ring 75 sections connected by locking devices, and a fabric cover removably connected with the frame ring.

9. A photographer's head screen comprising a stand composed of a collapsible post 80 and collapsible legs some of which are longer than the others and which are adapted to extend under the screen proper to prevent the stand from turning over, a clamp carried by the post and which is provided with devices 85 for adjusting it about a vertical axis, an inclined supporting rod detachably connected with the clamp, and a screen proper detachably connected with the inclined supporting rod.

10. A photographer's head screen comprising a stand composed of a collapsible post and collapsible legs some of which are longer than the others, a frame at the bottom of the post to which the inner ends of the legs are 95 pivoted, another frame secured to the post above the frame first mentioned, links connecting the shorter legs with the upper frame and slotted links connected at their inner ends to said upper frame and connected at their outer ends to the longer legs by pins which extend through the slots of the links.

11. A photographer's head screen comprising a stand, a screen, an inclined supporting rod for the screen, a bracket carrying a clamp for the supporting rod, a plug depending from the bracket, a block in the upper end of the stand into which the plug extends and in which it is free to turn to a limited extent, and means for holding the plug in set position.

In testimony whereof I have hereunto subscribed my name.

JULIUS JOE SCHUERMANN.
